UNITED STATES PATENT OFFICE.

JOSEPH GOODRICH, OF CHICAGO, ILLINOIS.

VICE.

SPECIFICATION forming part of Letters Patent No. 593,649, dated November 16, 1897.

Application filed August 7, 1897. Serial No. 647,482. (No model.)

To all whom it may concern:

Be it known that I, JOSEPH GOODRICH, a citizen of the United States, residing at Chicago, in the county of Cook and State of Illinois, have invented certain new and useful Improvements in Vises; and I do declare the following to be a full, clear, and exact description of the invention, such as will enable others skilled in the art to which it appertains to make and use the same, reference being had to the accompanying drawings, and to the letters of reference marked thereon, which form a part of this specification.

The invention relates to that class of vises in which the jaws can be quickly adjusted to the size of work to be operated upon and then by a supplemental action tightened upon the article inserted between them.

The object of the invention is to secure quick and reliable action and to provide for the control of the jaws wholly by means of pedals, so that the hands of the operator shall both be free to adjust the work. These objects are attained by the parts and arrangement of parts, as hereinafter fully described, and illustrated in the accompanying drawings, in which—

Figure 1 is a side elevation of the vise. Figs. 2 and 3 are sectional details on the lines 2 2 and 3 3, respectively, of Fig. 1. Fig. 4 is a detail elevation, and Fig. 5 is a sectional view on the line 5 5 of Fig. 4.

In vises of this type it is important that in spreading the jaws maintain their parallel relation, so that in gripping the work their coöperating faces are substantially parallel whether the article inserted between them is large or small. It is furthermore greatly to be desired that when the lever movement is employed in tightening the jaws upon the work the movable jaw be a lever of the first class, because of the great power of such a lever. I therefore employ a fixed and a movable jaw and swing the latter upon an adjustable pivot, means being provided for locking in its adjusted position the bar to which the jaw is pivoted. I further provide a pedal-controlled set of levers for spreading the jaws and springs for automatically closing them when the lever-pressure is released. I also provide a clutch for holding the slide-bar, which carries the pivot of the lever or

clamping-jaw, and an automatic controlling mechanism for releasing the clutch to admit of the adjustment of the jaws and reengage it when they are closed upon the work. Mechanism controlled by a pedal is also provided for rocking the lever-jaw upon its pivot for the purpose of firmly compressing it upon the work and by which it may also be released. The use of the hands in adjusting the jaws to the work is therefore wholly obviated.

The fixed jaw A is adapted to be secured to a bench, as X, as shown at a, and to have its lower end mortised into the floor Y, as shown at a'. The movable or clamping jaw is shown at B and is pivoted at c to a slide-bar C, which freely moves in a transverse slot in the jaw A sufficiently below the head of the vise, so as not to interfere with the work. Near the lower end of the jaws are a pair of parallel horizontal bars D, fixed to the jaw A and passing loosely through the jaw B, and E, fixed to the jaw B below the bar D and passing loosely through the jaw A. The adjacent edges of the bars D are spaced apart and are provided, respectively, with the rack-bars d e.

Contracting-springs F, located immediately below the bar C, and f, located below the bar E, connect and draw together the jaws A B. A pair of spreading-levers G G' are pivoted in vertical alinement to the jaw A, between the bars C and D, and are adapted to bear against the jaw B. These levers are each provided at its outer end with a roller g g, and the face of the jaw is channeled to receive them. A link-bar h connects the two levers G G' and is prolonged downwardly and provided with a pedal H. The lower end of the link-bar h may be provided with ratchet-teeth, as shown, to coöperate with a fixed pawl h', attached to the jaw B, so as to hold the jaws apart.

A clutch-block in the form of a roller K is set within a recess k in the rearward side of the jaw A, so as to coöperate with the slide-bar C, the face of which is preferably roughened, as shown at c'. The roller K is pivoted between a pair of bracket-arms l', projecting laterally from the upper end of a spring-rod L, the lower end of which is secured to the jaw A, as shown at l. The rod

L not only serves to carry the roller K, but by its spring action to hold it normally in engagement with the slide-bar C and the wall of the recess k.

5 The release mechanism for the clutch comprises a thrust-pin M, passing through the jaw A and bearing against the upper end of the rod L, and a cam-rod O, coöperating with the head m of the thrust-pin M. The rod O 10 is pivotally attached to the lever-arm G, and the parts are so disposed that when the lever-arm G is in its elevated position, as shown in solid lines in Fig. 1, the pressure upon the pin M of the cam portion of the rod O is relieved, so that the clutch-block K is forced into the recess k. As it is necessary that the 15 clutch mechanism be released before the jaws of the vise can be spread the roller ends of the lever G G' are normally slightly removed 20 from the face of the jaw B. When pressure is applied to the pedal II to throw these lever-arms down, the first action is to release the clutch mechanism.

A mutilated gear-wheel P, having a portion 25 of its periphery smooth, as shown at p, is located between the slide-bars D E, so as to coöperate with the racks d e. This gear-wheel is fixed upon a spindle R, which is journaled in horizontal slots in plates Q q, 30 fixed to the jaw A. The spindle R is provided with a crank-arm r, which projects loosely through a slot in a lever-arm S, pivoted at s to a plate T, fixed to the jaw A. The lever S is provided at its forward or free 35 end with a pedal-piece s', whereby it may be depressed against the resistance of a spring t, secured to the plate T. A spring-pawl U, carried by the lever S, coöperates with a ratchet t', formed upon the plate T, so as to 40 lock the lever S in any position to which it may be adjusted. The gear-wheel P is so set that when the lever S is in its elevated position the plain portion p of the gear is adjacent to the rack e, so that the bar E is released from engagement with the bar D and 45 leaves the jaw free to move as pressure is applied to the pedal II.

In operation the foot of the user is applied to the pedal II in order to spread the jaws 50 sufficiently to receive the work to be adjusted in the vise. The work having been inserted pressure upon the pedal may be at once released, allowing the jaws to close so as to grip the article and permitting the lever-arms G G' 55 to be drawn upwardly by the action of the spring g', thereby removing the cam-face of the rod O from the head of the pin M and permitting the clutch-block to enter into engagement with and thereby lock the slide-bar 60 C. The foot is now applied to the pedal s' so as to oscillate the gear-wheel P, which at once comes into engagement with the rack e and moves the lower end of the jaw B still farther away from the jaw A, rocking the jaw B upon 65 its pivot-pin e, and thereby tightening the grip of the jaws upon the work, the pawl U engaging the ratchet t', so as to maintain this

grip. In order to remove the work from the vise, the pawl U is disengaged from the ratchet and the spring t throws up the lever S, thereby 70 rotating the gear P and drawing in the lower end of the jaw B, so as to loosen the grip upon the work. If necessary, the foot may again be applied to the pedal II, so as to still farther spread the jaws, and, if desired, the ratchet 75 of the link-bar h may be engaged with the fixed pawl h', so as to hold the jaws in their spread position against the action of the closing-springs F f.

It will be seen that the manipulation of the 80 vise is wholly by pedal action, and that the gripping is accomplished by a system of levers of great power, so that as much pressure may be placed upon the work as may be desired. It will also be seen that the action is 85 very quick, the spreading being accomplished without any loss of time, and the gripping mechanism being ready for action without lost motion to whatever position the jaws may have been adjusted. 90

I claim as my invention—

1. The combination in a vise, with a fixed jaw, a clamping-jaw, a transverse bar in sliding engagement with the fixed jaw and in pivotal relation with the clamping-jaw, and a 95 clutch for locking the fixed jaw and the bar together, of pedal-actuated means for releasing the clutch and moving the clamping-jaw away from the fixed jaw.

2. The combination in a vise, with a fixed 100 jaw, a clamping-jaw, a transverse bar in sliding engagement with the fixed jaw and in pivotal relation with the clamping-jaw, and a clutch for locking the fixed jaw and bar together, of swinging arms pivoted to the fixed 105 jaw and adapted to bear against the clamping-jaw, clutch-releasing mechanism connected with the arms, and a pedal connected with the arms whereby they may be swung to release the clutch and move the clamping-jaw away from the fixed jaw. 110

3. The combination, in a vise with a fixed 115 jaw, a clamping-jaw, a transverse bar pivoted to the clamping-jaw and in sliding engagement with the fixed jaw, of means for sliding the bar to separate the jaws, and springs for drawing the jaws together.

4. The combination, in a vise, with a fixed 120 jaw, a transverse bar in sliding engagement with the fixed jaw, a clamping-jaw pivoted to the bar, and clutch mechanism for locking the bar and fixed jaw together, of swinging 125 arms pivoted to the fixed jaw and adapted to bear against the clamping-jaw, clutch-releasing mechanism operatively connected with the swinging arms, a pedal for swinging the arms to release the clutch mechanism and separate the jaws, springs acting upon the jaws in opposition to the separating-arms, and means for rocking the clamping-jaw on 130 its pivot.

5. The combination, in a vise, with a fixed 135 jaw, a transverse bar in sliding engagement with the fixed jaw, a clamping-jaw pivoted to

the bar, and clutch mechanism for locking the bar and fixed jaw together, of swinging arms pivoted to the fixed jaw and adapted to bear against the clamping-jaw, clutch-releasing mechanism operatively connected with the swinging arms, a pedal for swinging the arms to release the clutch mechanism and separate the jaws, and means for rocking the clamping-jaw on its pivot.

10 6. The combination, in a vise, with a fixed jaw, a transverse bar in sliding engagement with the fixed jaw, a clamping-jaw pivoted to the bar and means for locking the bar in an adjusted position, of spreading mechanism reacting between the lower ends of the two jaws for rocking the clamping-jaw on its pivot when the slide-bar is in any position to which it may be adjusted.

20 7. The combination, in a vise, with a fixed jaw, a transverse bar in sliding engagement with the fixed jaw, a clamping-jaw pivoted to the bar and means for locking the bar in an adjusted position, a pair of parallel rack-bars fixed one to each of the jaws, a mutilated 25 gear coöperating with the two rack-bars, and a pedal-actuated crank-arm for oscillating the gear.

8. The combination, in a vise, with a fixed jaw, a transverse bar in sliding engagement 30 with the fixed jaw, a clamping-jaw pivoted to the bar and means for locking the bar in an adjusted position, a pair of parallel rack-bars fixed one to each of the jaws, a mutilated gear coöperating with the two rack-bars, a

pedal-actuated crank-arm for oscillating the 35 gear, and a spring for normally holding the crank-arm in such position that the teeth of the gear are out of engagement with the rack attached to the clamping-jaw.

9. In a vise having spreading parallel jaws 40 and means for spreading the jaws, the combination with such parts of a pivot for one of the jaws, parallel rack-bars fixed one to each jaw, a mutilated gear interposed between and coöperating with the racks, a crank for 45 controlling the gear, and a spring for throwing such crank to such a position as to bring the toothless portion of the gear into juxtaposition with one of the racks.

10. In a vise, the combination with a fixed 50 jaw, a bar adapted to slide in a transverse aperture in such jaw, a movable jaw pivoted to such bar, and levers for forcing the movable jaw away from the fixed jaw, of clutch mechanism for locking the slide-bar to the 55 fixed jaw in any adjusted position, mechanism for releasing the clutch mechanism and being operatively connected with the jaw-moving levers, and means for disengaging the releasing mechanism from the clutch mechanism independently of the approach of the movable to the fixed jaw.

In testimony whereof I affix my signature in presence of two witnesses.

JOSEPH GOODRICH.
